Patented Dec. 9, 1975

237,993

TOY HEALTH CENTER

Osamu Takahashi, Tokyo, Japan, assignor to
Tomy Kogyo Co., Inc., Tokyo, Japan

Filed Aug. 27, 1974, Ser. No. 500,936

Term of patent 14 years

Int. Cl. D21—01

U.S. Cl. D34—15 AC

FIG. 1

FIG. 2

FIG. 3

FIG. 4

FIG. 5

FIG. 6

FIG. 1 is a front elevational view of the toy health center showing my new design;

FIG. 2 is a left side elevational view thereof;

FIG. 3 is a right side elevational view thereof;

FIG. 4 is a top plan view thereof;

FIG. 5 is a bottom view thereof; and

FIG. 6 is a rear elevational view thereof.

I claim:

The ornamental design for a toy health center, as shown and described.
